UNITED STATES PATENT OFFICE

ALWIN MITTASCH AND MARTIN MÜLLER-CUNRADI, OF LUDWIGSHAFEN-ON-THE-RHINE, GERMANY, ASSIGNEES TO I. G. FARBENINDUSTRIE AKTIENGESELLSCHAFT, OF FRANKFORT-ON-THE-MAIN, GERMANY

IRON CARBONYL COMPOSITIONS AND THEIR MANUFACTURE

No Drawing. Application filed April 22, 1925, Serial No. 25,141, and in Germany December 5, 1924.

This invention has as its object compositions of iron carbonyl which compared with pure iron carbonyl have the advantage of being less inflammable and less liable to self-ignition and in consequence thereof can be handled, shipped and stored with much greater convenience. The composition, in accordance with our invention, consists of iron carbonyl and hydrocarbons or mixtures of hydrocarbons or substitution products of hydrocarbons such for example as halogenated hydrocarbons or alcohols may be used and it is surprising that comparatively small additions of such solvents are sufficient to raise the ignition point very considerably. This circumstance is also of great importance for shipping as by reason thereof the freight rates are not unnecessarily increased. When it is desired to make stable compositions for warehousing, the addition of the said solvents may be greater than the approximate amount required for the desired degree of safety. In the latter case, the composition may consist of up to about 90 per cent, by volume, of the diluent and substantially more than 10 per cent, by volume, of iron carbonyl, while for transport the amount of the iron carbonyl should be higher for the reason stated above. The above described quantities of organic substances to be added to the iron carbonyl will be hereinafter referred to as stabilizing quantities. In addition to the aforesaid advantages, such compositions have also the property of giving off less obnoxious vapours. Generally such solvents are most suitable from a practical point of view as on the one hand are cheap and on the other hand do not interfere with or even assist the intended use of the iron carbonyl, and generally solvents of a low volatility are to be preferred. As an example we cite a mixture of equal parts of iron carbonyl and benzene or heavy gasoline of 0.75 specific gravity.

In the claims hereunto appended the expression "hydrocarbon body" is intended to cover hydrocarbons and halogenated substitution products of hydrocarbons, or alcohols.

We claim:

1. As a composition of matter a mixture of iron carbonyl with a hydrocarbon body

containing substantially more than 10 per cent, by volume, of iron carbonyl.

2. As a composition of matter a mixture of iron carbonyl with a halogenated hydrocarbon containing substantially more than 10 per cent, by volume, of iron carbonyl. 55

3. As a composition of matter a mixture of iron carbonyl with heavy gasoline containing substantially more than 10 per cent by volume of iron carbonyl. 60

4. As a composition of matter a mixture of iron carbonyl with a hydrocarbon containing about 50 per cent by volume of iron carbonyl. 65

5. As a composition of matter a mixture of iron carbonyl with heavy gasoline containing about 50 per cent by volume of iron carbonyl. 70

6. A process of increasing the stability of iron carbonyl and rendering it less inflammable which comprises adding thereto a stabilizing quantity of an organic solvent inert to said iron carbonyl. 75

7. A process for increasing the stability of iron carbonyl and rendering it less inflammable which comprises adding thereto an equal quantity of heavy gasoline. 80

In testimony whereof we have hereunto set our hands.

ALWIN MITTASCH.
